US0D1043246S

(12) **United States Design Patent** (10) **Patent No.:** **US D1,043,246 S**
(45) **Date of Patent:** **** Sep. 24, 2024**

(54) **BOTTLE**

(71) Applicant: **Ball Corporation**, Westminster, CO (US)

(72) Inventors: **Matthias van de Liefvoort**, Louisville, CO (US); **Linda A. Hines**, Westminster, CO (US)

(73) Assignee: **Ball Corporation**, Westminster, CO (US)

(**) Term: **15 Years**

(21) Appl. No.: **29/848,828**

(22) Filed: **Aug. 5, 2022**

(51) **LOC (14) Cl.** **07-01**

(52) **U.S. Cl.**

USPC **D7/509**; D7/619.1

CLAIM

The ornamental design for a bottle, as shown and described.

DESCRIPTION

FIG. 1 is a perspective view of a first embodiment of a bottle, showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a cross-sectional view thereof, taken along the line 8-8 in FIG. 6;

FIG. 9 is a perspective view of a second embodiment of a bottle, showing our new design;

FIG. 10 is a front elevation view thereof;

FIG. 11 is a rear elevation view thereof;

FIG. 12 is a right elevation view thereof;

FIG. 13 is a left elevation view thereof;

FIG. 14 is a top plan view thereof;

FIG. 15 is a bottom plan view thereof; and,

FIG. 16 is a cross-sectional view thereof, taken along the line 16-16 of FIG. 14.

The broken lines in the figures illustrate the portions of the bottle that form no part of the claimed design.

1 Claim, 14 Drawing Sheets
